JOSEPH B. KOPF, OF ROCKVILLE CENTER, NEW YORK

PAD FOR SADDLES

Application filed September 26, 1930. Serial No. 484,503.

The present invention relates to improvements in saddles, and more particularly it pertains to pads especially adapted for use with riding saddles.

5 It is one of the objects of the present invention to provide a saddle pad which will be possessed of sufficient resiliency to conform completely to the contour of the animal's back upon which it may be used.

10 It is another object of the invention to provide a saddle pad which will be of sufficient thickness to provide a pad of proper form and appearance, and at the same time a pad which will produce a great cushioning effect.

A further object of the invention resides in the provision of a saddle pad which, by reason of its soft, pliable and resilient nature, will not produce sores or abrasions.

20 With the above and other objects in view, reference is had to the accompanying drawings, in which—

Figure 1 is a perspective view of a saddle showing one of the saddle pads broken away to illustrate the under or inner face of a saddle pad constructed in accordance with the present invention, in elevation;

25 Figure 2 is a view, partly in section and partly in elevation, illustrating specifically the construction of a pad constructed in accordance with the present invention; and

30 Figure 3 is an enlarged detail sectional view taken through one of the saddle pads.

Referring specifically to the drawings, 10 35 designates the saddle proper, which has, as is customary, side flaps 11 upon the under or inner faces of which are engaged suitable pads 12 which are secured to the body of the saddle.

40 It is to the construction of the saddle pad 12 that the present invention particularly pertains, and it contemplates combining in a saddle pad a plurality of elements of different degrees of resiliency which, when employed in the manner hereinafter described, 45 combine to produce a saddle pad having all of the attributes heretofore mentioned.

Referring again to the drawings, the saddle pad 12 consists of a layer of felt 13 of 50 a yieldable or pliable nature, which is shaped

to the desired form. Adjacent to and in contact with this yieldable layer 13 there is a resilient layer 14, which latter may consist of sponge or foam rubber. These two layers 13 and 14 may be attached together 55 by suitable adhesive material, if desired, and these two layers form the main body portion of the pad.

That layer of the pad designated 15 is formed from lamb's wool which still remains 60 attached to the hide or pelt 16, which latter provides for the attachment of the lamb's wool layer 15 to the resilient layer 14 as by a suitable adhesive.

The reference character 17 designates the 65 outer or finishing layer and this layer is formed of leather. It will be noted that the outer layer 17 is so shaped as to fold or roll around the edges of the several layers 13, 14 and 15, as designated at 18 in Figure 3, thus 70 producing a neat appearing finish to the edge of the pad, as well as providing a protection to the edges of these layers to prevent fraying thereof. To enhance the appearance of the saddle pad, the edges of the 75 several layers may be shaped, as indicated at 20, to aid in producing the desired roll to the defining edge of the finished pad.

In the present embodiment of the invention, there is illustrated a waterproof lining 80 21 for the layer 17 of leather, but this lining is not essential to the successful functioning of the pad and may be entirely omitted, if desired. When I employ a waterproof lining such as 21, however, I desire to use rubberized cloth or similar suitable material, and I prefer not to attach it to either the lamb's wool or the leather, the lining being held in position by the line of stitching 22 which is also employed to secure the defining 85 edge of the leather 17 to the felt layer 13, and the said lining acting to prevent perspiration from the horse penetrating to the lamb's wool layer 15.

90 From the foregoing, it will readily be apparent that the present invention provides a new and novel saddle pad in which all of the attributes set forth in the recitation of the objects of the invention are obtained, and while the invention has been herein 100

illustrated in a preferred form it is to be understood that it is not to be limited to the specific construction herein illustrated but may be practiced in various other forms which rightfully fall within the scope of the appended claims.

What is claimed is:

1. A pad for saddles comprising a pad of felted material, a layer of lamb's wool, a layer of resilient material interposed between the felted material and the layer of lamb's wool, and a finishing cover completely enclosing the defining edges of said layers of material and secured to the pad of felted material.
- 10 2. A saddle pad comprising a layer of felt, a layer of sponge rubber secured to said layer of felt, a layer of lamb's wool secured to said layer of sponge rubber, and a finishing cover formed of leather and completely enclosing said layer of lamb's wool, and the defining edges of all of said layers and secured to the exposed face of said layer of felt.
- 15 3. A saddle pad comprising a layer of felt, a layer of sponge rubber secured to said layer of felt, a layer of lamb's wool secured to said layer of sponge rubber with its hide face in contact therewith, and a leather covering completely enclosing the defining edge of each of said layers of material and secured to the layer of felt by a line of stitching.
- 20 4. A saddle pad comprising a layer of felt, a layer of sponge rubber, and a layer of lamb's wool, all of said layers of material being secured together, a leather covering therefor and completely enclosing the defining edges of said layers of material, and a waterproof lining interposed between said leather covering and the next adjacent layer of material.
- 25 5. A saddle pad comprising a layer of felt, a layer of sponge rubber, and a layer of lamb's wool, all of said layers of material being secured together, a leather covering therefor and completely enclosing the defining edges of said layers of material, and a waterproof lining interposed between said leather covering and the next adjacent layer of material, said waterproof lining being unattached to said leather covering and the next adjacent layer of material except at the edge of the waterproof lining.

In testimony whereof I have affixed my signature.

JOSEPH B. KOPF.
